CLAIM

The ornamental design for a external connector plug, as shown and described.

DESCRIPTION

FIG. 1 is a front, left, and bottom side perspective view showing our new design for a external connector plug;

FIG. 2 is a rear elevation view thereof;

FIG. 3 is a right side elevation view thereof; and,

FIG. 4 is a top plan view thereof.

The broken lines showing throughout the drawings are included for the purpose of illustrating environment structure only and forms no part of the claimed design.
